UNITED STATES PATENT OFFICE.

CHARLES SAMUEL FRANKLIN, OF SAINT MICHAELS, ENGLAND, ASSIGNOR TO RADIO CORPORATION OF AMERICA, A CORPORATION OF DELAWARE.

THERMIONIC VALVE.

Application filed June 11, 1924, Serial No. 719,253, and in Great Britain June 20, 1923.

This invention relates to triode valves and its object is to produce a valve capable of producing high frequency oscillations of considerable power.

5 In a valve as usually constructed the connections to the grid and to the cathode are brought out through the same end of the valve and in consequence there is a very intense and concentrated high tension high frequency field acting on the glass which supports the grid and cathode. This results in a limitation of the voltage and therefore of the power at which the valve can be worked since the glass around the grid and cathode seals 10 or supports quickly gets heated and may even be melted so that the valve is destroyed.

As a result of numerous experiments I have discovered that by arranging the seals and supports of the grid at one end of the valve 20 and those of the cathode at the other end of the valve I can avoid this concentrated field and its effects.

According to this invention therefore I construct a valve in which the grid is supported 25 from one end of the valve through which its connection is sealed and the cathode is supported at the other end of the valve through which its connections are sealed. The invention is particularly applicable in the case of 30 valves in which the envelope is mainly formed of metal which functions as the anode. In such a case I weld to each end of the metal cylinder which forms the anode a glass cylinder or bulb and I support the cathode from 35 one of these bulbs through which I seal the connections and I support the grid from the other bulb and seal its connection therein. In the case of a valve having a glass envelope I support and seal the grid and cathode at 40 opposite ends and I support the anode and arrange the anode supports and seal approximately midway between the two ends.

45 My invention is illustrated by the accompanying drawing, in which Figs. 1 and 2 are longitudinal cross sections through valves constructed in accordance therewith.

50 A is a metal cylinder which acts as the anode. B is a glass cylinder which is sealed to one end of A and to which is sealed a metal plate or cap C. The other end of A is sealed to a glass cylinder or bulb D. The grid G is supported by stout rods E carried by the plate or cap C, while the cathode F is sealed into the bulb D.

For short waves particularly it is very important that the grid supports E E should be 55 very substantial and rigid as they have to carry large high frequency currents and any lack of rigidity seriously affects the constancy of wave-lengths.

60 Such a valve is much more reliable than a valve made with the grid and cathode brought out at the same end, and can be worked to higher voltages. The heating of the glass due to high frequency fields is reduced to a 65 minimum.

Having described my invention what I claim is:—

1. A vacuum tube device comprising a tubular metal anode, a vitreous closure sealed 70 to one end thereof and having a re-entrant portion, a cathode member positioned within said tubular anode and having supporting members sealed through said re-entrant portion, a second vitreous portion sealed to the 75 other end of said tubular anode, a metal closure therefor, sealed thereto, and a grid electrode member attached to said second metallic closure member.

2. A vacuum tube device comprising a tubular metal anode, a vitreous closure sealed to 80 one end thereof and having a reentrant portion, supporting means sealed in said reentrant portion, a cathode member positioned within said tubular anode carried by said 85 supporting means, a vitreous cylinder sealed to the other end of said tubular anode, a metal closure sealed to the open end of said vitreous cylinder, supporting members carried by said last named metal closure, and a control 90 electrode member positioned between said anode and cathode carried by said supporting members.

3. A vacuum tube device having an envelope comprising a tubular metal portion, a 95 vitreous closure for one end thereof, an electrode supported by said vitreous closure, a metallic closure for the other end of said tubular metal portion, an electrode carried by said metallic closure, and a vitreous member 100 between said tubular metal portion and said metal closure.

4. A vacuum tube device having an envelope comprising a tubular metal cylinder, a vitreous closure having a reentrant portion 105 for one end of said cylinder, a metal cap for the other end of said cylinder and a tubular vitreous insulating member between said

tubular metal cylinder and said metal cap, said tubular vitreous member being hermetically sealed at opposite ends to said tubular metal cylinder and the edge of the metal cap.

5. A vacuum tube device comprising a tubular metal anode, a vitreous closure sealed to one end thereof, an electrode member positioned within said tubular anode and having supporting means extending through said end, a second vitreous portion sealed to the other end of said tubular anode, a metal closure therefor, and another electrode member attached to said metallic closure member.

CHARLES SAMUEL FRANKLIN.
